UNITED STATES PATENT OFFICE

MAURICE J. SCHLESS, OF NEW YORK, N. Y.

JEWEL SETTING

Application filed August 4, 1930. Serial No. 472,867.

This invention relates to settings for jewels and other ornamental stones.

The primary object of the invention is to provide a setting which will expose the total display face of an ornamental stone or jewel to the fullest possible extent as distinguished from present settings which, in many instances, conceal a portion of the stone or jewel adjacent the edges thereof under the metal plate in which the jewel is set. In accordance with this aspect of the invention, the jewel is disposed within an aperture in a plate, which is of a diameter greater than the diameter of the jewel.

Another object of the invention is to provide a setting which will give the appearance of containing a stone of a larger size than that actually contained therein. Accordingly, the jewel is set within a hole in a plate, the diameter of the plate being somewhat greater than the diameter of the stone and beads are formed on the plate having continuations which overlie the edges of the stone to hold it in place and which beads give the impression of prongs holding a larger stone.

It is also an object of the invention to provide a setting whereof portions give the appearance of being a part of the jewel, thus making the jewel appear larger than it is. To this end, surfaces are formed on the setting which lie in substantially the plane of the facets of the jewel thereby reflecting light to the eye at substantially the same angle as do the surfaces of the facets.

Still another object of the invention is the provision of reflecting areas for the purpose of supplementing the lustre of the jewel. In accordance with this aspect of the invention, the beads or prongs are formed with plane surfaces which present reflecting areas supplementing the reflecting areas of the stone.

The invention also seeks to provide a jewel setting wherein the jewel appears to be of a more valuable shape or cut than that actually in the setting. To this end, grooves are formed in the surface of the plate having angular bottoms whereof the dihedral edge of the groove gives the effect of being the edge of the stone.

These and other objects of the invention

and the means for their attainment will be more apparent from the following detailed description, taken in connection with the accompanying drawings illustrating one embodiment by which the invention may be realized, and in which:

Figure 1 is a view showing, in plan, the display face of a jewel mounted in my novel setting.

Figure 2 is a view, in plan, showing a plate for a jewel setting constructed according to my invention.

Figure 3 is a sectional view taken on line 3-3 of Figure 1 and shows a jewel mounted in the setting.

Figure 4 is a fragmentary sectional view taken along the line 4-4 of Figure 1 but on a larger scale, and showing a jewel with its edge in spaced relation to the setting.

Figure 5 is an enlarged sectional view taken along line 5-5 of Figure 1 showing details of the securing means for the jewel.

Referring to Figures 3 and 4, a substantially rectangular box-like member 10, having cut away portions 11, forms the base or support for the jewel setting of this invention and is well known to the trade.

Superimposed upon the box 10 is a plate 12 made of any suitable metal for jewelry settings, which plate 12 is provided with an opening 13, preferably centrally located, which is tapered to conform generally to the shape of a jewel or other ornamental stone 14 to be mounted therein. The opening 13 is of a shape to conform to that of the jewel 14 but preferably slightly larger than the transverse dimensions of the jewel except at spaced points where contact shoulders or abutments 15, Figure 2, are formed on the plate 12 upon which the anterior surface of the jewel rests, in such manner that the edge of the jewel is maintained in spaced relation to the edge of the hole 13 in the plate 12 for the major portion of its periphery. The jewel is secured in position upon the shoulders 15 and in the plate 12 by overlapping beads 16 superimposed upon portions of the plate 12 adjacent to the shoulders 15 and extending rearwardly to overlie the edge of the jewel and in contact therewith. The beads 16 are secured to said

plate by soldering or the like, or the beads 16 may be made an integral part of the plate 12 and compressed to overlap the jewel 14 and thus secure the same. The beads 16 are shown as having two upper or display surfaces 17 having a common edge 18, tapering to a raised corner 19, proximate to the corners of the plate 12. The two surfaces 17 present reflecting areas which supplement the lustre 10 of the jewel in such manner that light is reflected from a larger area than from merely the surfaces of the stone 14.

Furthermore, these beads 16, since they extend inwardly from the corners of the plate 12, give the appearance of prongs holding a stone much larger than is actually in the setting.

In order to give the impression to the eye of the observer that the stone 14 is of a greater diameter and of a more valuable shape, than it actually is, a groove 20, 21 (Figure 4) is formed in a definite manner upon the plate 12 at the sides adjacent to the exposed edges of the jewel 14 and between the beads 16. The metal of the plate 12 is cut to a maximum depth at the line 22 and surface 20 is formed in substantially the plane including the edge 23 between adjacent facets 24, 25 of the jewel 14. The outer face 21 of the groove is so formed as to provide an edge 26 on the surface of the plate 12 parallel to the outer edge 27 thereof. The edges 27 and 26 form the margins of the surface 30, which connects the ledges 31 to form an even surface 30, 31, which, running the entire periphery of the plate 12, appears as the square sides of a box holding a square stone. The surface 20 joins the surface 21 at the bottom of the groove in a straight line 22, which is also parallel to the sides of the plate 12. The surfaces 20 form reflecting surfaces whereof the inner edges 34 conform to the edges 35 of the stone and the surfaces 20 give the effect of continuations of the facets of the stone by reflecting light therefrom at substantially the same angle as the facets. The straight line 22 in the bottom of the groove 20, 21, gives the effect of being the edge, of the stone, thus the effect is that the stone is made to appear larger than it really is. The reflections from the surfaces 20 occurring at two spaced points at the edges of the plate 12 (which surfaces 20 are in substantial continuation of the adjacent facets of the stone) merge with the reflection from the said facets of the stone and, together with the reflection from the inclined surfaces 17 of the beads 16, present a display surface which is a substantial square 50 as distinct from a round surface and this enlarged surface thus appears of larger area than the actual face of the stone.

While in the embodiment illustrated, the opening is circular to accommodate a stone with a round face, it is to be understood that

it can be formed to follow the contour of a square or rectangular stone or any shape known to the lapidary art and in the case of a square stone, surfaces 20 can be formed to continue the display surfaces of the stone 70 without appearing to change the shape thereof. The plate 12 with the stone mounted therein may then be attached to the box in any well known manner, as by soldering and thus affixed to the body of the article of 75 jewelry which the stone is to ornament.

It will thus be seen that there is provided a new and useful setting or mounting for stones which firmly secure them without concealing the face of the stone where it is not clutched and which, by a novel formation, has lustrous surfaces which appear to be a part of the stone and which greatly enhance the appearance there.

Various modifications will occur to those skilled in the art in the composition, configuration and disposition of the component elements going to make up the invention as a whole, as well as in the selection and combination of such component elements and no limitation is intended by the phraseology of the foregoing specification or illustrations in the accompanying drawings, except as indicated in the appended claims.

What is claimed is:—

1. In a jewelry setting, means formed with a receiving aperture for a jewel, spacing means to prevent contact between the major portion of the jewel and the inner surface of the aperture, jewel engaging means comprising inclined reflecting surfaces lying in planes substantially the same as the adjacent facets of the jewel, and recessed reflecting surfaces adjacent the exposed edges of the jewel formed in the body of the setting. 100

2. In a jewelry setting, means formed with a jewel receiving aperture, spacing means to prevent contact between the major portion of the jewel and the edge of the aperture, and jewel engaging means lying in planes substantially the same as the adjacent facets of the jewel carried with the first named means and extending from the outer marginal surface of said first named means. 110

3. In a jewelry setting, means formed with a jewel receiving aperture, spacing means to prevent contact between the major portion of the jewel and the edge of the aperture, and jewel engaging means lying in planes substantially the same as the adjacent facets of the jewel carried with the first named means and over the spacing means, and extending from the outer marginal surface of said first named means. 120

4. A jewelry setting for an ornamental stone comprising a rectangular plate formed with an aperture to receive the stone, abutments thereon upon which the stone seats and means to engage the stone comprising a raised bead formed with reflecting surfaces down- 125

wardly inclined from a common edge forming a projection of the common edge of the adjacent facets of the mounted stone.

5 5. In a jewelry setting, a rectangular plate formed with an aperture to receive a jewel, raised shoulders therein against which a jewel seats, securing beads adjacent the shoulders and recessed reflecting surfaces adjacent the edges of the aperture, said surfaces substantially continuing the plane of proximate facets of the jewel.

10 6. In a jewelry setting, a rectangular plate having a mounting aperture with seating abutments, securing means adjacent the abutments, and recessed reflecting surfaces adjacent to and spaced from the exposed edge of the stone following the contour thereof at the edge proximate the stone and terminating in a groove parallel to the side of the plate.

15 20 7. A jewelry setting comprising a rectangular plate formed with a jewel receiving aperture, means to maintain the jewel in spaced relation to the walls of the aperture, beads carried with the surface of the plate 25 engaging the jewel, angular grooves formed in the plate between the beads and parallel to the sides of the plate, the side of said groove adjacent the aperture lying in a plane substantially the same as the plane of the proximate facets of the jewel.

25 30 8. In a jewel setting, a plate formed with a jewel receiving aperture, means to maintain the jewel in spaced relation to the walls of the aperture, jewel engaging means carried 35 with the plate and having reflecting surfaces, said plate being formed with angular grooves between the said engaging means parallel to the sides of the plate, the sides of said grooves adjacent the aperture lying in planes substantially the same as the plane of the proximate facets of the jewel.

In testimony whereof I affix my signature.
MAURICE J. SCHLESS.
